UNITED STATES PATENT OFFICE.

GEORGE H. FORSYTH, OF CHICAGO, ILLINOIS.

DISK WHEEL.

1,427,366.

Specification of Letters Patent. Patented Aug. 29, 1922.

Original application filed November 26, 1918, Serial No. 264,253. Divided and this application filed February 21, 1921. Serial No. 446,862.

To all whom it may concern:

Be it known that I, GEORGE H. FORSYTH, a citizen of the United States, residing at Chicago, in the county of Cook and State 5 of Illinois, have invented certain new and useful Improvements in Disk Wheels, of which the following is a specification.

This application is a division of my co-pending application Serial No. 264,253.

10 The invention of this application relates to metal wheels of the disk type adapted for use in connection with pneumatic tires.

The principal object of the invention is to conform and construct the disk in its 15 peripheral portion adjacent the felly and rim so as to afford ready access to the valve stem of the pneumatic tire carried thereby.

I have found it advantageous to construct the disk body of a wheel of curved 20 radial cross-section or at an inclination to the plane of the wheel in order to impart thereto a substantial degree of resiliency under road stresses. As the valve stem ordinarily lies in the median plane of a

25 wheel, the crossing of such plane by the disk adjacent the periphery thereof involves interference between the valve stem and disk and renders the former difficult of access.

30 According to the present invention, the aforementioned difficulty is solved by providing the disk with an aperture substantially in line with the valve stem axis, through which the valve stem may project 35 or be reached; or, alternatively, by forming a depression or pocket in the disk to accommodate the valve stem or to afford room for effecting an air pipe coupling therewith.

40 In order that the invention may be readily understood, I have in the accompanying drawings set forth preferred and modified embodiments thereof as an illustrative basis for the description of the invention.

45 In the drawings—

Fig. 1 is a fragmentary side elevation of a wheel embodying the invention with a portion thereof broken away to show the valve stem;

50 Fig. 2 is a transverse section through the peripheral portion of the wheel shown in Fig. 1;

Figs. 3, 4 and 5 are views similar to Fig. 2 but showing modified provision for the 55 valve stem,

Having particular reference to Figs. 1 and 2 of the drawing, corresponding to Figs. 1 and 2 of the parent application, the single disk 11 of the wheel is shown, throughout the greater portion of its periphery, as extending radially at 12 to the point 13 and thence horizontally at 14 towards the rear and thence radially at 15, and terminating in an inclined lip for supporting the rear side of the demountable rim 16. At intervals, however, pockets 17 are formed in the rear of the wheel by bending the metal radially at 18 from near the point 13 to the point 19 and thence in a general horizontal direction to the rear underneath the 70 rim. The purpose of this pocket 17 is to bring the wall 18 nearer the rim-retaining shim 20 to enable the use of short bolts 21 as a securing means.

The crossing of the median plane of the 75 wheel by the disk portion 14 intercepts the valve stem 22 and, to accommodate the latter, the disk is apertured at 23 for the passage therethrough of the valve stem and cap.

In Fig. 3, corresponding to Fig. 8 of the 80 parent application, a peripheral fragment of a wheel is illustrated having two disks 24 and 25. In the present case the general line of the disk 25 is substantially radial as indicated by the position of the reference 85 numeral, but at the point corresponding axially with the valve stem 22, and possibly at other points corresponding to the shim securing bolts 21, the disk 25 is depressed inwardly to form pockets 26 for 90 the housing of the valve stem which is thereby rendered readily accessible from that side of the wheel, the base portion of the valve stem in this case, passing through the horizontal portion 25^a of the disk 25 as 95 well as the portion 24^a of the disk 24.

In that form of construction shown in Fig. 4, corresponding to Fig. 11 of the parent application, the wheel is shown as comprising two disks 27 and 28 spaced apart, 100 the disk 28 extending in a sweeping curve as indicated by the reference numeral throughout the greater portion of its peripheral extent. At a point, however, corresponding to the location of the valve stem, the disk 28 105 is depressed inwardly at 29 to the position indicated in section at 28^a from which position the disk is reversely bent, intercepting the axis of the valve stem 22 and thence radially at one side of the valve stem and 110

again horizontally. Here, as in the former instances, the wheel disk intercepts the median plane of the wheel and the axis of the valve stem, an aperture being provided therethrough for the accommodation of the valve stem and, as in Fig. 3, a pocket housing for the valve cap 22^a being provided.

In Fig. 5, corresponding to Fig. 14 of the parent application, the disks 30 and 31 embrace the valve stem 22 immediately beneath the rim 16 and for a slight distance therebelow. In order to give access to the valve stem and cap, the disk 31 is provided with a depression or pocket 32 into which the valve stem cap projects through an aperture 33 in the upper wall 32^a of the pocket 32.

It is obvious, the essential object of the invention being to provide access to the valve stem, that the particular location of the aperture or of the pocket is not of moment, and will be controlled by the cross-sectional contour of the disk employed and by the taste of the designer affecting his choice of having a smooth uninterrupted front face with access to the valve stem from the rear, or a broken front face with access to the valve from the front; the terms "front" and "rear" and their use in connection with the illustration and description of the invention being relative only and not terms of limitation. Moreover, it will be understood that the several embodiments of the invention illustrated and described herein are intended as exemplifications only, the invention obviously being susceptible of embodiment in various other modifications without departure from the essence thereof or sacrifice of its

material advantages, wherefore the illustration and description are to be taken in an illustrative and not in an unnecessarily limiting sense. 40

I claim:

1. The combination of a wheel having a disk body, a felly, a tire-carrying rim, and a tire having a valve stem, the disk body having a portion intercepting the valve stem axis and apertured at the point of interception for affording access to the valve stem. 45

2. The combination of a wheel having a disk body, a felly, a tire-carrying rim, and a tire having a valve stem, the disk body having a portion intercepting the axis of the valve stem and apertured at said point of interception and the valve stem extending through said aperture. 50

3. The combination of a wheel having a disk body, a felly, a tire-carrying rim, and a tire having a valve stem, the disk body having formed therein a depression spaced from the felly and extending across the median plane of the wheel and including the valve stem axis, that part of the disk body forming the upper wall of the depression apertured and the valve stem extending therethrough into the pocket to render the same 65 accessible. 55

In testimony whereof I have hereunto subscribed my name in the presence of two subscribing witnesses.

GEORGE H. FORSYTH.
